US00D556680S

(12) **United States Design Patent** (10) Patent No.: **US D556,680 S**
(45) Date of Patent: **** Dec. 4, 2007**

(54) **BATTERY FOR VIDEO CAMERA**

(75) Inventor: **Hiroyuki Matsumoto**, Kadoma (JP)

(73) Assignee: **Matsushita Electric Industrial Co., Ltd.**, Osaka (JP)

(**) Term: **14 Years**

(21) Appl. No.: **29/272,038**

(22) Filed: **Jan. 31, 2007**

(30) **Foreign Application Priority Data**

Aug. 10, 2006 (JP) 2006-021315

(51) **LOC (8) Cl.** 13-02

(52) **U.S. Cl.** **D13/103**

(58) **Field of Classification Search** D13/102-106, D13/110, 118-119, 184; 429/96-100, 163, 429/176

See application file for complete search history.

(57) **CLAIM**

I claim the ornamental design for a battery for video camera, as shown and described.

DESCRIPTION

FIG. 1 is a front perspective view of a battery for video camera of the present invention;

FIG. 2 is a rear perspective view thereof;

FIG. 3 is a front view thereof;

FIG. 4 is a first side view thereof;

FIG. 5 is a second side view thereof;

FIG. 6 is a top view thereof;

FIG. 7 is a bottom view thereof; and,

FIG. 8 is a rear view thereof.
